M. WALTON

ANTIFREEZING PUMP

Filed April 9, 1924

UNITED STATES PATENT OFFICE.

MARK WALTON, OF ULLIN, ILLINOIS, ASSIGNOR OF ONE-HALF TO ALONZO S. DALE, OF ULLIN, ILLINOIS

ANTIFREEZING PUMP.

Application filed April 9, 1924. Serial No. 705,288.

To all whom it may concern:

Be it known that I, MARK WALTON, a citizen of the United States, and a resident of Ullin, in the county of Pulaski and State of Illinois, have invented a new and useful Improvement in Antifreezing Pumps, of which the following is a full, clear, and exact description.

My invention relates to improvements in anti-freezing pump, and it consists in the combinations, constructions, and arrangements herein described and claimed.

An object of my invention is to provide an anti-freezing pump which has novel means for permitting the water in the pipe to flow back into the well to prevent the freezing of the water in the winter time as stated, this water is led back into the well instead of draining into the ground as is usually the case. This prevents the ground adjacent to the pump from becoming sloppy.

A further object of my invention is to provide a device of the character described in which the means for permitting the water to flow back into the well is adapted to retain the water disposed between the pump cylinder and the water in the well, this water being used as a prime for the next pumping operation.

A further object of my invention is to provide a device of the character described which is simple in construction and which may be readily attached to a standard pump, thus converting the standard pump into an anti-freezing pump.

Other objects and advantages will appear in the following specification, and the novel features of the invention will be particularly pointed out in the appended claims.

My invention is illustrated in the accompanying drawing, forming part of this application, in which—

Figure 1 is a side elevation of the device as shown operatively applied to a pump,

Figure 2 is an enlarged detailed section of the device, and

Figure 3 is an enlarged sectional view of the valve.

In carrying out my invention, I make use of a pump 1 which has a standard pipe 2 in communication therewith and which is provided with a pump cylinder 3. The cylinder is disposed a sufficient distance below the surface of the ground so as to prevent

freezing of the water within the cylinder. By operating the handle 4, the piston, not shown, within the cylinder 3 is actuated and sucks the water through the screen 5 and forces it out through the mouth 6 of the pump.

My attachment comprises a cylinder 7 in which a float 8 is slidably disposed. The cylinder is placed in communication with the pipe 2 by means of pipes 9, 10, and 11. It will be noted from Figure 2 that the pipes 9 and 10 extend above the cylinder 3 and communicate with the portion of the pipe 2 that is disposed between the cylinder 3 and the pump 1. The pipe 11 is placed in communication with the pipe 2 that depends from the cylinder 3. The float 8 is provided with a guide 12, the lower end of this guide being provided with a needle valve 13. The bottom of the cylinder 7 has a conical shaped recess 14 that is adapted to receive the valve 13. The recess 14 is in communication with the interior of the cylinder 7 and with the pipe 11.

From the foregoing description of the various parts of the device, the operation thereof may be readily understood. When the water is received in the cylinder 7 it is adapted to raise the float 8 so as to open the valve 13 and permit this water to drain through the pipe 11 and back into the pipe 2.

In this manner the water disposed in the section of the pipe 2, that is positioned between the cylinder 3 and the pump 1, is drained off and is returned to the well and is not drained into the ground as is usually the case. The pump 1 may be operated in the ordinary manner and suck the water through the screen 5 and force it out through the outer opening 6 of the pump.

The pipes 9, 10, and 11 are so small that they will not interfere with the normal operation of the pump. As soon as the pumping operation is stopped however, the water disposed between the cylinder 3 and the pump 1 drains through the pipe 10 and flows into the cylinder 7. The pipe 9 is an air pipe and permits the water to drain through the pipe 10. The cylinder 7 retains this drained water for a short time, due to the fact that the needle valve 13 is closed.

As soon as the water has risen to a predetermined level within the cylinder 7, the valve 13 will be opened and will permit the water to drain through the pipe 11.

and back into the well. The water will continue to flow back into the well as long as the valve is open. The valve will seat, however, before all of the water in the cylinder 7 drains therefrom. The closing of the valve 13 retains the water in the pipe 11 and the portion of the pipe 2 disposed below the pump cylinder. This water is used for priming when the pump is again operated.

10 The device is attached to the pump portion and the latter is then disposed in the ground and after the pump has been driven into place, the earth is filled around the attachment, as shown in Figure 1 to prevent the water in the cylinder 7 and cylinder 3 from freezing. The cylinder 7 and cylinder 3 are disposed a sufficient distance below the surface of the ground so as to obviate any freezing of the water within the cylinders.

15 20 The device is simple in operation and provides a novel means for draining the water from the pipe 2 disposed adjacent to the surface of the ground, and at the same time retaining a sufficient amount of water to be used as a prime for the next pumping operation.

I claim:

1. The combination with a pump cylinder, a vertical pipe in communication with one 30 end of said cylinder and a second pipe in communication with the other end of said cylinder, of an auxiliary cylinder in communication with said pipes, said auxiliary cylinder adapted to permit the water to flow from the pipe disposed above said pump cylinder through the auxiliary cylinder and into said second named pipe and means disposed in said auxiliary cylinder for retain-

ing a sufficient quantity of water for priming.

40

2. The combination with a pump cylinder, a vertical pipe in communication with one end of said cylinder and a second pipe in communication with the other end of said cylinder, of an auxiliary cylinder in communication with said pipes, said auxiliary cylinder adapted to permit the water to flow from the pipe disposed above said pump cylinder through the auxiliary cylinder and into said second named pipe, a float 50 in said cylinder, and a needle valve actuated by said float, said valve being adapted to close so as to normally retain a sufficient amount of water in the pipe disposed below said pump cylinder for priming the pump 55 cylinder.

45

3. The combination with a pump cylinder, a vertical pipe in communication with one end of said cylinder and a second pipe in communication with the other end of said cylinder, of an auxiliary cylinder in communication with said pipes, said auxiliary cylinder adapted to permit the water to flow from the pipe disposed above said pump cylinder through the auxiliary cylinder and into said second named pipe, a float 60 in said cylinder, a needle valve actuated by said float, said valve being adapted to close so as to normally retain a sufficient amount of water in the pipe disposed below said 65 pump cylinder for priming the pump cylinder, and an air pipe in communication with said auxiliary cylinder and with the pipe disposed above said pump cylinder.
